UNITED STATES PATENT OFFICE.

EDWARD M. STEPHENS, OF NEW YORK, N. Y.

SELF-CLOSING DEVICE FOR WINDOWS.

932,569.

Specification of Letters Patent. Patented Aug. 31, 1909.

Application filed February 18, 1909. Serial No. 478,668.

To all whom it may concern:

Be it known that I, EDWARD M. STEPHENS, a citizen of the United States, and a resident of Richmond Hill, in the borough of Queens, 5 city of New York, county of Queens, and State of New York, have invented certain new and useful Improvements in Automatic Self-Closing Devices for Windows, of which the following is a specification, reference being had to the accompanying drawings, in which—

Figure 1 is an elevation of the outside of a window provided with my invention, parts being shown broken away for greater clearness; Fig. 2 is a sectional detail view on enlarged scale taken on the line 2—2 of Fig. 3, viewed in the direction of the arrow; Fig. 3 is a vertical section taken on the line 3—3 of Fig. 1 and viewed in the direction 20 of the arrow; Fig. 4 is an elevation of a detail of the upper fusible link on a still more enlarged scale; Fig. 5 is a central longitudinal section of Fig. 4; Fig. 6 is a vertical central section on enlarged scale of the 25 lower fusible link.

My invention relates particularly to that class of windows, used in so-called "fire-proof construction", of the type known as "double-hung" windows comprising two 30 substantially vertically movable sashes in which each sash is counter-balanced by its own separate weight, and the frames and sashes of which are of relatively incombustible material, for instance such as are 35 known in the trade as "Kalamein" in which the sashes and frames are constructed of wood covered by metal, or so-called "hollow metal" in which the frames and sashes are composed of metal.

40 The object of my invention is to provide means whereby the closing of windows of the class referred to may be automatically insured in the presence of high temperatures, as for instance of conflagrations when 45 it becomes desirable to close the windows to cut off drafts and thus prevent spread of fire, and to accomplish these objects by means more certain and invariable in operation and more simple and economical in 50 construction than heretofore.

I attain these objects by my invention, as follows:

Referring to the drawings, Fig. 1 represents one of the aforesaid double-hung windows comprising upper sash A and lower sash B mounted and vertically movable as usual in the usual frame C, the construction shown in the drawings being of the so-called hollow metal type in which the frame and sashes are composed of metal. To lower sash B is secured the usual counterweight b, shown in dotted lines in Fig. 3, by means of a flexible connection, in this instance a chain b' movably supported in the usual manner by pulley b². It will be observed that b' instead of being secured as usual to the top of sash B passes through the frame of said sash to its point of attachment at the lower part thereof where it is secured in any convenient manner as for instance by the screw b³. The flexible connection or chain b' between sash B and counterweight b is provided with two fusible links. One of these b⁴ is of the well known type and located as shown in Fig. 3 slightly above sash B in such position as to insure its holding sash A in closed position when said link is fused as hereinafter described. The other of said fusible links b⁵ is located at the extremity of said fusible connection b' and as more clearly shown in Fig. 6 passes through the sash so as to expose its fusible part on the weather or outer side of said sash. Both of said fusible links b⁴, b⁵, consist generally speaking of two metal members b⁶, b⁷, normally united by a part b⁸ composed of more fusible metal than that mentioned, as for instance a solder fusible at approximately say 165° F. The upper sash A is provided with means to connect it with the aforesaid counterweighting device of sash B on fusion of either of said more fusible parts of the links b⁴, b⁵, and in the present instance I have shown such means as consisting of the arm a containing slot a' through which chain b' passes and disposed and dimensioned to movably guide said chain. It will be observed however that the link b⁴ is provided with a part b⁹ larger than the aperture of said slot a' which, on release of 100

chain b' by severance of said links through fusion, engages with said arm a , thus transferring to the latter and its connected sash A the upward pull of counterweight b . Sash 5 A is provided with a counterweighting device of similar character to that described for sash B, that is to say a flexible member or chain a^2 connecting said sash A with counterweight a^3 shown in dotted lines in Fig. 3.

The operation of the device is as follows:—Both said sashes A and B are normally in approximate equilibrium with their respective counterweights, thus facilitating 15 their vertical movements in opening and closing the sashes. One of the fusible links e^6 connected with sash B is as aforesaid disposed so that its more fusible part is exposed to the weather or outer side of said sash. 20 The other of said fusible links b^4 is disposed so as to be exposed on the indoor side of said sashes. In the event of an exterior or interior conflagration it is desirable that both sashes should be closed to obstruct passage 25 of drafts or flames. Assuming that the sashes have been left partly open and that the outdoor temperature is raised by an exterior fire to a point sufficient to fuse the more fusible part b^8 of link b^6 this will immediately sever connection of chain b' with sash B. Sash B relieved of its counterweight 30 will close by gravity. Chain b' will be pulled upward by its counterweight until expanded portion b^9 of link b^4 engages 35 against arm a of sash A whereby counterweight b is applied to sash A forcing latter to rise to closed position. Thus both sashes are simultaneously automatically closed by 40 release of the one from its counterweighting device and by transference of said counterweighting device to the other. In case of a similar rise of temperature on the inside of the sashes, the fusible link b^4 being located within will be severed by fusion of its more 45 fusible part b^8 and with the same result as aforesaid.

By my invention as described I am enabled to effectuate promptly the automatic closing of both sashes and with I believe the least 50 possible interference with their present conventional construction and with the least possible addition of extraneous devices and parts, thus effecting the desired result by the simplest possible and most certain means 55 and at minimum expense. It will be understood that in Fig. 3 the sashes, frames and other parts are indicated as broken to economize space in drawing; also that my invention is equally applicable to the "Kalamein" 60 system of construction in which the frames and sashes are of wood covered by metal, in which case it is only necessary to bore a channel for the chain b' through the wooden and metal portions of the sash. It will also 65 be understood that preferably each sash, as

shown in Fig. 1, is, as usual, equipped with two counterweighting devices as above described, one for each side of the sash.

My invention is not confined to the particular forms of construction shown in the 70 drawings, pulleys, chains, fusible links, etc. as equivalents of those shown may be employed without departing therefrom.

I am aware that single sashes have been automatically closed by devices depending 75 upon the fusibility of portions of their counterweighting devices, and do not wish to be understood as broadly claiming such means for insuring the closing of a single sash, but I am not aware that in double-hung sash or window construction means have hitherto been devised for effecting their closure by release of the one from its counterweighting device and simultaneous transference thereof to the latter.

What I claim as new and desire to secure by Letters Patent is the following, viz:—

1. In a window device, the combination of a vertically movable lower sash, a counterweight, a flexible connection between said sash and counter-weight, a part of said flexible connection more fusible than its adjoining parts, a vertically movable upper sash, another counter-weight, another flexible connection between said last mentioned sash and said last mentioned counter-weight, an arm carried by said upper sash and means to connect said arm with said first mentioned flexible connection on fusion of said more fusible part thereof.

2. In a window device, the combination of a vertically movable lower sash, a counterweight, a flexible connection between said sash and counter-weight, two parts of said flexible connection the one part disposed on the weather and the other part on the indoor side of said sash, both said parts being more fusible than adjoining parts of said flexible connection, a vertically movable upper sash, another counter-weight, another flexible connection between said last mentioned sash and said last mentioned counter-weight, an arm carried by said upper sash and means to connect said arm with said first mentioned flexible connection on fusion of either of 115 said more fusible parts thereof.

3. In a window device, the combination of a vertically movable lower sash, a counterweight, a flexible connection between said sash and counter-weight, said connection having on the outside of said sash a part more fusible than adjoining parts and on the inside and above said sash another part also more fusible than adjoining parts of said connection, a vertically movable upper sash, 125 another counter-weight, another flexible connection between said last mentioned sash and said last mentioned counter-weight, an arm carried by said upper sash and means to connect said arm with said first mentioned 130

flexible connection on fusion of either of said more fusible parts thereof.

4. In a window device, the combination of a vertically movable normally lower sash, a counterweight, a chain connecting said sash and counterweight and having an expanded portion and below said portion a part more fusible than its adjoining parts, a vertically movable upper sash provided above said expanded portion with a member containing a slot disposed and dimensioned to movably

guide therethrough said chain and engage with its said expanded portion, another counterweight, another chain, connecting said last mentioned sash with said last mentioned counterweight and means to movably support said last mentioned chain.
